UNITED STATES PATENT OFFICE.

ADOLPH K. MALMQUIST, OF SOUTH BELLINGHAM, WASHINGTON, ASSIGNOR TO THE MALMQUIST MACHINE COMPANY, OF SOUTH BELLINGHAM, WASHINGTON.

SHEET-METAL CONTAINER FOR FOOD.

Application filed January 6, 1922. Serial No. 527,395.

To all whom it may concern:

Be it known that I, ADOLPH K. MALMQUIST, a citizen of the United States, and a resident of South Bellingham, in the county 5 of Whatcom and State of Washington, have invented certain new and useful Improvements in Sheet-Metal Containers for Food; and I do hereby declare the following to be a full, clear, and exact description of the invention, such as will enable others skilled in 10 the art to which it appertains to make and use the same.

This invention relates to an improvement in sheet metal containers for food and more 15 particularly to such as are employed in the canning industry.

It has been proposed to hermetically seal 20 in cans, both solids and liquids, and to perform the operations of supplying liquid to a can containing solids while in a vacuous chamber and of afterward sealing a cap to the can while still in the vacuous chamber. Such a method is disclosed in Letters Patent 25 No. 1,386,887 granted to me on the 9th day of August 1921. In carrying out such a method, uniformity, simplicity and flexibility of construction of the end members (especially the bottom members) of the cans are matters of importance to insure the 30 proper filling and sealing of the cans without danger of loss of liquid.

In the method disclosed in my said former patent, a can containing solid food is enclosed in a vacuous chamber and while in 35 said chamber the can is raised to a liquid supplying means and its internal capacity is reduced (by bowing the bottom of the can inwardly) while it is being supplied with liquid. The can is afterwards lowered 40 (when its bottom will be permitted to assume its original form), and then transferred to means which will seam a cap to its upper end, while the can is still in the vacuous chamber.

45 One object of my present invention is to so construct a can that the method of canning above outlined shall be facilitated; so that the bottom of the can shall be such that it may be readily flexed to cause it to bow inwardly to reduce the internal capacity of the can when the latter is presented to the liquid supplying means, and so that said bottom may be permitted to flex in the reverse direction when the can descends from 50 the liquid supplying means and bulge out-

wardly to so increase the internal capacity of the can that the liquid level may descend below the level of the solid contents of the can, whereby the can (containing both solids and liquid) may be transferred to seaming 60 means without danger of spilling any of the liquid and whereby also the cap may be applied and seamed to the filled can without danger of squeezing any of the liquid from the can by pressure upon the solid contents. 65

With the above stated and other objects in view, the invention consists in certain novel features as hereinafter set forth and pointed out in the claims.

In the accompanying drawings; Figure 1 70 is a view in elevation of a can body having a bottom end member in accordance with my improvements, seamed thereto; Figures 2 and 3 are views showing the can cap or top member; Figures 4, 5 and 6 are views 75 of apparatus to illustrate the manner in which the can may be manipulated prior to, during and subsequent to the supplying of liquid to the can, and Figure 7 is a view of the sealed and finished can showing the positions which the end members will assume 80 after the filled and sealed can shall have been removed from the vacuous chamber.

My improved can comprises a sheet metal body member 1; a sheet metal bottom member 2 having air tight union with the lower edge portion of the body member, and a top or cap member 3 to be seamed to the upper edge portion of the body member 1. The bottom member 2 is so formed that it shall 85 be flexible and may normally bulge outwardly or downwardly, but so that it shall be capable of being caused to bow inwardly and afterwards (when the can is filled with in a vacuous chamber) to bulge outwardly. 90 In order to guard against warping of the bottom members of cans and insure the retention of their proper shape, so that they may be stacked in a seaming machine and accurately fed from the stack, the bottom member may be formed with an annular bead or corrugation 4 near its peripheral portion. The construction of the cap or top member 3 may be similar to that of the bottom member and provided with an annular bead or corrugation 4. In Figures 2 and 3 however, the cap or top member is shown as having its major portion normally flat. In any event the top member 3 must be sufficiently flexible to be capable of being 100 105 110

caused to bow inwardly when on a filled can and exposed to atmospheric pressure. The cap or top member should not, however, be concave normally,—viz. before it shall have been seamed to a filled can, because such concave cap might press liquid out of the can when it is forced on by the chuck of a can sealing mechanism.

The importance of the flexible end members and particularly the construction of the bottom member, when the cans are employed for canning liquid with solids while the cans are enclosed in vacuum chambers, will be apparent from the following explanation of the manner in which the cans are manipulated during the method of filling cans containing solids, with liquid.

A portion 5 of a can filling machine is shown in Figures 4, 5 and 6 and it may be assumed that the chamber 6 has been exhausted. It may also be assumed that mechanism (not shown) may be employed for applying caps and seaming them to the can bodies while in said exhausted chamber. In Figures 4 to 6 I have shown a vertically movable platform 7 which receives a can 1 containing solid food and having (in Figures 4 and 6) the outwardly or downwardly bulged or bowed bottom 2. In the top portion of the chamber is a disk 8 to enter the open upper end of the can when the latter has been raised as in Figure 5 and a gasket 9 is also provided to receive the upper edge of the open can body 1. A casing 10 for a valve 11 is located over the top of the casing forming the vacuum chamber 6 and communicates through a duct 12 with said chamber so as to discharge liquid (from a convenient source of supply, not shown) to a can when the latter is in the raised position shown in Figure 5. The can platform 7 is made with a central opening for the accommodation of a rod 13 and its head 14, the lower end of said rod being secured to 45 and carried by a vertically movable plunger 15. A roller 16 is mounted at the lower end portion of the plunger 15 and with this roller, a cam 17 is cooperable to move the plunger vertically,—said cam being secured to an operating shaft 18 of the canning machine. The upper end of the plunger 15 may be made with a recess 19 in which a spring 20 may be seated, the upper end of said spring bearing against the bottom of 55 the can platform 7.

As previously stated, the bottom 2 of the can is flexible and normally bulged outwardly or downwardly and when in this condition, it will be supplied with a solid food and inserted into the chamber 6, after which, the said chamber will be exhausted. The platform will be caused to rise and the upper edge of the can be caused to bear against the gasket 9,—the displacement disk 60 or plate 8 entering the can and displacing

the contents sufficiently to accommodate the cap or top member which will be subsequently seamed to the can. After the upper end of the can shall have been pressed against the gasket 9 and thus temporarily closed, 70 continued upward movement of the plunger 15 will cause the head 14 on the rod 13 to press the can bottom 2, upwardly or inwardly, causing it to bow inwardly as shown in Fig. 5, thus reducing the internal capacity 75 of the can. The valve 11 may now be opened to permit the filling of the can with liquid which will percolate through the solid food and into the pores thereof and cover the said solid food. As the can descends from 80 the position shown in Figure 5, the descent of the plunger 15 will cause the headed rod 13 to descend the extent permitted by the spring 20 before the upper end of the can leaves the gasket 9. During such preliminary descent of the rod 13, pressure of its head 14 against the flexible can bottom 2 will be relieved and the weight of the contents of the can will cause said flexible bottom to become convex or bulged outwardly 85 or downwardly as it was when the can was first introduced into the chamber 6. Such downward or outward bulging of the flexible bottom 2 will have the effect of increasing the internal capacity of the can,—in 90 other words restoring the can to its original internal cubic area. By thus increasing the internal capacity of the can after the liquid shall have been discharged thereinto, the level of the liquid in the can will be caused to descend (see x Figure 6) below the level x^1 of the solid food and hence there will be no danger of spilling any of the liquid from the can while the latter is being transferred from the liquid filling means to the sealing or cap placing and seaming mechanism. Furthermore, the cap or top member of the can may be pressed in position and seamed to the top of the can body without danger of squeezing or pressing liquid from the 95 can during such capping operations.

In the event that the weight of the contents of the can should be found to be insufficient to cause the bottom member to readily flex from its inwardly bowed or 100 concave position to its outwardly bulged or convex position, resort might be had to magnetic or other means.

When the filled and sealed can shall have been removed from the vacuum chamber in 105 which the liquid filling and after the can sealing operations had been performed in vacuum, atmospheric pressure will cause both flexible heads to become bowed inwardly or concaved so that the finished, 110 filled and sealed can, when exposed to atmospheric pressure will have the appearance as indicated in Figure 7 and the can will be well filled from one end member to the other.

The word "normally" as applied to the condition of the can bottom is intended to mean the condition of the bottom before the can is subjected to a vacuum, or when the can is unsealed or when it is empty.

Having fully described my invention what I claim as new and desired to secure by Letters Patent, is:—

1. A sheet metal can for use in a process 10 of canning substantially as described, comprising a body member, a flexible bottom member normally bulging outwardly and capable of being bowed inwardly, the structure and flexibility of said bottom member 15 being such that when bowed inwardly, the said bottom member may be automatically returned to the outwardly bulging form by the weight of the contents of the can and further that it may finally be bowed inward- 20 ly by atmospheric pressure after the can shall have been sealed in vacuum.

2. A sheet metal can for use in a process 25 of canning substantially as described, comprising a body member, a flexible bottom member normally bulging outwardly but capable of being bowed inwardly, the structure and flexibility of said bottom member being such that when bowed inwardly, the said bottom member may be automatically 30 returned to the outwardly bulging

form by the weight of the contents of the can, and a flexible top-member to be sealed to the can, both of said bottom and top members having such flexibility that they will be caused to flex or bow inwardly by atmospheric pressure after the can shall have been sealed in vacuum.

3. A sheet metal can for use in a process of canning substantially as described, comprising a body member and two flexible end members, the end member for the bottom of the can being normally outwardly bulging and having such structure and flexibility that when initially bowed from convex to concave form, it may be automatically returned to the outwardly bulging form by the weight of the contents of the can, said end members having such flexibility that they will finally be bowed inwardly by atmospheric pressure after the can shall have been sealed in vacuum, and each of said end members having an annular bead near its peripheral portion.

In testimony whereof, I have signed this specification in the presence of two sub- 55 scribing witnesses.

ADOLPH K. MALMQUIST.
